UNITED STATES PATENT OFFICE.

FREDERICK B. THATCHER, OF PROVIDENCE, RHODE ISLAND.

DESIGN FOR A BOTTLE-STOPPLE.

SPECIFICATION forming part of Design No. 34,955, dated August 20, 1901.

Application filed March 9, 1901. Serial No. 50,520. Term of patent 14 years.

To all whom it may concern:

Be it known that I, FREDERICK B. THATCHER, a citizen of the United States, and a resident of Providence, in the county of Providence and State of Rhode Island, have invented and produced a certain new and original Design for a Bottle-Stopple, of which the following is a specification, reference being had to the accompanying drawings, forming part thereof.

Figure 1 is a top or plan view of my new design. Fig. 2 is a view in side elevation of the same.

As the stopple is shown in the drawings the leading or material feature of my design resides in the peculiar configuration of the article as seen from the side, the stopple having a distinct projection *b* at the top and another, *c*, equally marked at the bottom, the cen-

tral portion longitudinally and located between these projections consisting of two disk-shaped parts *a'* *a''*, larger than the projections. The upper disk-shaped part *a'* is the larger of the two central portions, and the lower central portion *a''* has a chamfered portion *a''* at the lower edge, this cylindrical portion with a chamfered lower edge forming a striking feature of the design.

Having described my invention, what I claim as new, and desire to secure by Letters Patent, is—

The design for a bottle-stopple as herein shown and described.

FREDERICK B. THATCHER.
